UNITED STATES PATENT OFFICE.

GUSTAVUS E. STRAUSS, OF NEW YORK, N. Y.

CURTAIN-POLE.

SPECIFICATION forming part of Letters Patent No. 444,230, dated January 6, 1891.

Application filed February 8, 1890. Serial No. 339,736. (No model.)

To all whom it may concern:

Be it known that I, GUSTAVUS E. STRAUSS, of the city, county, and State of New York, a citizen of the United States, have invented 5 certain new and useful Improvements in Curtain-Poles, of which the following is a specification.

This invention has reference to an improved curtain-pole of that class that is intended to 10 be used for curtains, lambrequins, portières, and the like, said curtains being readily applied without the use of tacks, hooks, pins, screws, or other fastening devices, and thereby conveniently suspended without tearing or 15 damaging the curtains in the least; and the invention consists of a curtain-pole made of two hinged semicircular sections which are connected by clamping-bolts and screw-nuts, so as to be firmly applied to the curtains, which 20 are clamped between the sections of the pole. The curtain-pole is provided with slots or openings for the suspension-bolts that are attached by screw-nuts to the supporting-brackets of the pole, as will be fully described 25 hereinafter, and finally pointed out in the claims.

In the accompanying drawings, Figure 1 represents a front elevation of my improved curtain-pole. Fig. 2 is a top view of the same, 30 and Figs. 3 and 4 are vertical transverse sections of the pole respectively on lines xx and yy , Fig. 2.

Similar letters of reference indicate corresponding parts.

35 In the drawings, A and A' represent the two semicircular sections of my improved hollow curtain-pole, which sections are connected at one side by hinges aa , while at the opposite side they are applied to the curtains 40 to be suspended from the pole. The sections A A' are connected by fastening-bolts B and thumb-nuts B', which are screwed onto the ends of said bolts, said bolts being attached to the section A and passed through slots b 45 of the section B'. By the connecting bolts and nuts a positive clamping action of the sections A A' on the goods is obtained, so that the reliable suspension of the curtains or hanging material is obtained. The curtain-

50 pole A A' is suspended from supporting-brackets C C, which are attached in the usual manner to the wall by means of hangers D, which are provided at the lower end with an arc-shaped piece D', that is inserted into slots or openings d in the upper part of the pole 55 and placed transversely thereto. The slots or openings d are formed of adjoining recesses in the upper parts of the semicircular sections A A', as shown clearly in Fig. 2. The hangers D are threaded at their upper ends and 60 clamped by thumb-nuts D² and washers d' to the arms of the supporting-brackets C, so that the pole is thereby firmly supported on the brackets C. The hanger D is readily inserted by placing its hanger-plate D' in line with 65 the slot d and then turning the hanger so as to place the hanger-plate D' transversely or at right angles to the slot d , in which position the clamping-connection with the supporting-bracket C is made. In this manner the simple 70 suspension of the curtain-pole is obtained. The pole-sections may be made of wood, metal, or other suitable material and provided with ornamental pole ends of any suitable shape. 75

The advantages of my improved curtain-pole are that by the same the hanging material may be suspended without attaching the same to the poles, so as to obviate the objectionable fastening of lace and other expensive curtains. As the clamping action is given by the sections of the pole, all special 80 fastening devices may be dispensed with, and thereby the curtain be removed or replaced without requiring specially skilled hands for 85 this purpose.

Having thus described my invention, I claim as new and desire to secure by Letters Patent—

1. The combination, with hollow semicircular sections hinged together at one side, of fastening-bolts attached to the inside of one section and extended through slots of the other section, and screw-nuts applied to the outer threaded ends of the fastening-bolts, 90 substantially as set forth.

2. The combination of a curtain-pole provided with longitudinal slots or openings,

with hanger - bolts having hanger - plates placed transversely to said slots, screw-nuts applied to the outer threaded end of said hanger - bolts, and supporting - brackets to 5 which the hanger-bolts and screw-nuts are applied, substantially as set forth.

In testimony that I claim the foregoing as

my invention I have signed my name in presence of two subscribing witnesses.

GUS. E. STRAUSS.
